UPHOLSTERY FASTENER

Le Roy S. Meyer, Englewood, N. J.

Application May 3, 1955, Serial No. 505,755

8 Claims. (Cl. 45—138)

The present invention relates generally to an improved upholstery device, and to an improved construction in upholstered furniture. In particular, it relates to an improved device for securing tufting buttons and similar articles to an upholstered piece of furniture, as well as to the resulting furniture construction.

It is common practice in the manufacture of upholstered furniture to tuft the faces thereof and to this end to employ tufting buttons, decorative or otherwise. The purpose of the tufting is to improve the construction of the upholstered furniture, as well as to enhance the appearance thereof. In accordance with the conventional tufting method, a long double-pointed needle carrying a twine is passed through the padded or stuffed portion of the section to be tufted and returned to substantially its point of entry. The twine is brought into engagement with the open or closed shank eye of the tufting button, the twine drawn taut to effect the tufting, and then knotted, the loose ends of the twine being snipped to complete the operation. This procedure is time-consuming if done properly, and for efficient operation requires the use of expensive and highly skilled labor. Moreover, the resulting construction possesses numerous disadvantages. The tufting twine is often frayed and ultimately severed by the eye shank of the tufting button, thereby releasing the tufting and the tufting button and greatly impairing the appearance of the furniture. To replace the tufting and the tufting buttons requires the services of a skilled upholsterer. When the furniture is reupholstered, the tufting operation must be repeated. In addition, when slip covers are placed on the furniture, the tufting and the tufting buttons are completely hidden, thereby greatly detracting from the appearance of the particular article of furniture.

It is thus a principal object of the present invention to provide an improved upholstery device.

Another object of the present invention is to provide an improved construction in upholstered furniture.

Still another object of the present invention is to provide an improved device for effecting the tufting of upholstered furniture.

A further object of the present invention is to provide an improved device for securing tufting buttons or ornaments to upholstered furniture.

Still a further object of the present invention is to provide an improved device for the tufting of furniture which may be quickly and simply applied and which is rugged and enduring.

Another object of the present invention is to provide an improved device for the tufting of furniture which permits the application of covers thereto which will assume the outline of the tufted surface.

Other and further objects of the present invention will in part become apparent and in part specifically pointed out in the following description of an illustrative embodiment, taken in conjunction with the accompanying drawing, wherein

Figure 1 is an exploded perspective view of one form

2

of improved tufting device constructed according to and embodying the device of the present invention;

Figure 2 is a transverse, sectional view of the device applied to a section of upholstered furniture, the tufting button and upholstery cover being shown in detached position by broken line; and

Figure 3 is a transverse, sectional view of the upholstery dress cover showing an alternative form of opening outlined by thread.

- 10 The present invention contemplates the provision of a tufting device comprising a stud element including a head portion and an elongated shank, locking means adapted to engage said shank, a button element, and separable fastening means adapted to releasably secure the button element to the head portion of said stud element. The improved device is applied to upholstered furniture by passing the stud shank through the front face of the base covering of an upholstered furniture section, through the tufting therein and through the rear base covering 20 of said section, to place the surrounding portion under compression, applying the lock device to the shank, applying an upholstery covering to the furniture, said covering having an opening registering with the stud head, and fastening the button to the stud head whereby 25 to releasably secure the covering thereto.

In the drawing annexed hereto and forming a part hereof, numeral 10 generally designates an elongated stud having a disc shaped head portion 12 and a rearwardly longitudinal, axial shank portion 14 which includes a forward section 16 tapering into an intermediate section 18 of reduced cross section which terminates in a pointed tip 20. Head 12 has a recess or well 22 formed therein which communicates with a tapped bore 24 coaxially formed in the shank forward portion 16.

- 30 35 A button 26 is provided which includes a cylindrical head 28 provided with a rearwardly projecting axial threaded shank or screw element 30 which is the counterpart of the tapped bore 24 and is adapted to releasably engage said bore. Button head 28 is provided, in a conventional manner, with a decorative covering 33 which may (but need not be) be formed of an upholstery material similar to that employed in covering the corresponding article of furniture.

40 A conventional suitable locking device such as a lock plate or speed nut 32 is provided, which mates with stud shank 14 and is adapted to engage and lock the same tightly. Stud 10, as well as button core 26, may be formed of any suitable material such as brass, aluminum, steel, plastic or the like, whereas the lock plate 32 is 45 preferably formed of a hardened spring steel in the well-known manner.

In Figure 2 of the drawing, the improved tufting device is illustrated as applied to a section of upholstered furniture constructed in the conventional manner. The section includes a front pad 34 formed of cotton, felt or the like over a rear stuffing material 36 formed of rubberized or natural hair, or any other suitable material. The front face of the upholstered section is provided with a muslin covering 38 and the rear section is 55 covered with a burlap webbing 40, all as is the usual practice. The shank of stud 10 is inserted into the upholstered section by passing the shank 14 thereof through muslin 38, pad 34, stuffing 36, and the burlap webbing 40, pointed tip 20 facilitating the piercing of the various 60 materials and layers, the tip 20 passing through and past the burlap backing 40 and being partially exposed.

Lock plate 32 is then applied to the stud shank 14 and urged towards the head portion thereof to effect therebetween the compression of the various layers in the vicinity of the stud 10 and to tuft same.

A plurality of studs 10 are applied as aforesaid in any desired pattern or arrangement to the upholstered article

of furniture and thereafter an upholstery or dress covering 42 is applied in the conventional manner. The upholstery or dress covering 42 may be formed of fabric, leather, plastic or the like and is provided with a plurality of openings 44 spaced in accordance with the pattern or arrangement of studs 10 carried by the upholstered article and registering with the heads 12 thereof. Each of the circular openings 44 in the upholstery covering may, but need not necessarily be, reinforced by a suitable grommet 46. The upholstery covering is secured to the confronting face of the muslin covering 38 by passing threaded shanks 30 of buttons 26 through openings 44 in the dress covering into engagement with the tapped bores 24 of studs 10, and buttons 26 are tightly screwed thereinto, firmly locking the respective sections of the upholstery covering 42 to the associated stud heads 12 so that the upholstery covering assumes and closely follows the tufted appearance of the corresponding surface of the upholstered furniture article.

It should be noted that stud head recess 22 is of slightly greater diameter than the periphery of the grommet 46 so that the latter may nest in recess 22, as illustrated in the drawing. When ordinary sewing thread-outlined openings 44 are used as desired, as shown in Figure 3, instead of grommets 44, the same nesting of the threaded marginal openings 45 in recess 22 may well be of advantage in reducing overall extension of the button and in insuring a tight fit. The upholstery buttons 26 may be easily replaced, as is apparent, merely by unscrewing one button and inserting another. Moreover, when a slip cover, constructed in accordance with the present invention, is applied to furniture, it may likewise be provided with openings as 44 or 44' arranged in the pattern of the studs 10. In such event, the buttons 26 are merely removed and are reinserted through the respective openings in the applied slip cover, which then will assume the tufted configuration of the furniture. It will be obvious that the illustrated construction and the improved tufting device may be employed in any type of upholstered furniture such as chairs, sofas, settees, couches and the like. The coverings so applied may be removed easily and quickly, for cleaning and replacement, as desired. Differently decorated buttons 26 may be used as desired, to achieve different effects, etc.

While there has been described and illustrated hereinabove a preferred embodiment of the present invention, it is apparent that numerous alterations and omissions may be made without departing from the spirit thereof.

Having now described my invention, what is claimed and desired to be secured by Letters Patent is:

1. An improved upholstered furniture construction comprising a pair of spaced webbings, a stuffing material disposed between said webbings, a plurality of spaced studs each having a head member abutting an outer face of one of said webbings and a shank portion passing

through said stuffing and said webbings and engaged by a locking element abutting the outer face of the other of said webbings, said webbings and the interposed material in the vicinity being compacted by and between said stud heads and said locking elements, a covering superimposed upon one of said webbings and having openings therein registering with said stud heads, and a plurality of button elements each having a shank portion registering with a corresponding covering opening and releasably secured to a respective stud head.

2. An improved construction in accordance with claim 1, wherein said studs have tapped axial bores formed therein communicating with said stud heads, and the shanks of said buttons are threaded releasably to engage said tapped bores.

3. An improved construction in accordance with claim 1, wherein the openings in said dress covering are outlined by and reinforced with grommets.

4. An improved construction in accordance with claim 3, wherein said stud heads have wells formed therein and said grommets nest in said corresponding wells.

5. An improved construction in accordance with claim 1, wherein said stud shanks are tapered to points at their ends opposite the head ends thereof.

6. An improved construction in accordance with claim 1, wherein said buttons are provided with covers of a material similar to that of said covering.

7. An upholstery cover fastening device comprising a stud that is formed at one end to penetrate through the upholstery and formed at the other end with an enlarged head adapted to engage and lie against one side of the upholstery when the stud is thrust thereinto, an outwardly open recess in said stud head, a separable button member consisting of a head portion and a shank disposed in said recess, said shank and recess having cooperating formations for releasably securing them together, so that after the stud is thrust into the upholstery and said cover mounted on the upholstery the button member shank may be inserted through a suitable opening in the cover to be secured within said recess and said cover is clamped between the stud and button heads.

8. The fastening device defined in claim 7 wherein said stud recess and button shank are in threaded engagement in assembly.
